UNITED STATES PATENT OFFICE

102,402

DESIGN FOR A CLAMP HANDLE

Herbert E. Tautz, Milwaukee, Wis., assignor to Delta Manufacturing Company, Milwaukee,
Wis.

Application October 19, 1936, Serial No. 65,371

Term of patent 7 years

To all whom it may concern:

Be it known that I, Herbert E. Tautz, a citizen of the United States, residing at 620 East Vienna Avenue, in the county of Milwaukee and State of Wisconsin, have invented a new, original, and ornamental Design for Clamp Handles, of which the following is a specification, reference being had to the accompanying drawing, forming part thereof.

In said drawing:

Fig. 1 is a side elevation of a clamp handle showing my new design.

Fig. 2 is a top view, and
Fig. 3 is a bottom view.

I claim:

The ornamental design for a clamp handle as shown.

HERBERT E. TAUTZ.
